Primary Examiner — Mary Shannon Malley*Assistant Examiner* — Dustin Andrew Griffith(74) Attorney, Agent, or Firm — Gearhart Law, LLC(57) CLAIM

The ornamental design for a wallet, as shown and described.

DESCRIPTION

FIG. 1 is a first perspective view of the wallet.

FIG. 2 is a second perspective view thereof.

FIG. 3 is a top view thereof.

FIG. 4 is a bottom view thereof.

FIG. 5 is a first side view thereof.

FIG. 6 is a second side view thereof.

FIG. 7 is a back view thereof.

FIG. 8 is a front view thereof.

FIG. 9 is an alternative perspective view of the wallet with a closure mechanism.

FIG. 10 is an alternative perspective view of the wallet with another closure mechanism; and,

FIG. 11 is an alternative perspective view of the wallet with yet another closure mechanism.

The broken lines in FIGS. 9–11 showing a closure mechanism depict portions of the wallet that form no part of the claimed design. The broken lines in FIG. 9 illustrating cards depict environmental subject matter and form no part of the claimed design.

1 Claim, 8 Drawing Sheets(56)
